MULTIPLEX RECEIVING APPARATUS

Alfred Kahn, Ozone Park, N. Y., assignor to
 Radio Corporation of America, a corporation of
 Delaware

Application February 25, 1933, Serial No. 658,620

6 Claims. (Cl. 178—50)

This invention relates to multiplex telegraph receiving systems, and has for its principal object to provide, in such a system, a method of and apparatus for easily and efficiently assigning the 5 received signals to the different channels. More specifically, an object is to provide a receiving system which is simple in construction, easy to maintain and which requires a minimum number of parts.

10 The present invention, although not limited thereto, finds particular application to multiplex systems of the time division type, and for this reason the invention will be described with special regard thereto. In multiplex systems of the 15 time division type the successive basic units of each channel are divided into equal portions of like number as the several channels, and the transmitting circuit is assigned consecutively to successive channels for a time interval equal at 20 most to one of these portions, the remaining portion of each basic unit of each channel being discarded and subsequently restored at the receiving end of the circuit. Such a multiplex arrangement is described in United States Patent No. 25 1,979,484, granted November 6, 1934, to R. E. Mathes.

In brief, the present invention comprises a coupling system for assigning the received incoming signals to their respective channels, and 30 for enabling the received signals to be rebuilt to their original form as at the transmitting station, whereby the suppressed portions of the transmitted signals are restored. For effecting this purpose, use is made of a coupling electron 35 discharge device whose normal condition of electrical stability is changed upon the flow of signal currents in the input circuit of the receiving arrangement.

Referring to the single drawing accompanying 40 this specification, there is shown a receiving circuit arrangement for a multiplex system in accordance with the present invention. This arrangement comprises, essentially, an energy collector or antenna 1, an amplifier and detector 45 circuit 2 adapted to receive radio frequency energy from the antenna and to detect same in a manner well known in the art, a tone keyer 3 under control of apparatus 2 for transmitting over a land line 4 to the receiving station A audible frequency tone which is interrupted in accordance with received signal energy, an amplifier and 50 rectifier circuit 5 for producing the envelope of the keyed tone, coupling tube 6 and a so-called kicker arrangement 7 with associated apparatus 55 for assigning the incoming signals to their re-

spective channels, each of the channels having a locking circuit 8 for rebuilding the received signal and transmitting the restored signal to a suitable utilization circuit 18.

Amplifier-detector apparatus 2 and tone keyer 5 3 have been shown merely in conventional form since the manner of receiving signals over an antenna and subsequently amplifying and detecting the signals to operate a tone keyer is well known in the art. For a more detailed description, however, of the operation of the tone keyer circuit reference is made to United States Patent No. 1,874,866, granted to H. H. Beverage, et al., particularly that portion which relates to Figure 2 thereof. 10

Similarly, amplifier-detector apparatus 5, which also is of a well known type, has been indicated in box form, the output or full wave rectifier part only being shown in order to illustrate its manner of connection to the coupling tube 6. 20 Only the negative pulses of the rectified signal are applied to the grid of tube 6 since the positive end of the rectifier is tied down to the filament which is at ground or zero potential. A low pass filter 9 consisting of series inductance 25 and shunt capacitance is utilized for smoothing out whatever tone components remain in the rectified signal.

In the circuit diagram shown, coupling tube 6 is biased by means of a grid battery 10 to pass current normally, in which condition there exists a positive potential on its anode which is lower in value than the potential of the anode supply $+E_b$, due to the IR drop in resistance 11. The receipt of a signal pulse on the grid of tube 6, however, is arranged to bias the grid so negatively as to make the tube block, that is, cease passing current, at which time the voltage on the anode of tube 6 will rise to the maximum value of $+E_b$, since at this time no current flows in the resistance 11. 30

Although this particular manner of operating tube 6 has been described, it will readily be understood that the invention is not limited thereto, since the desired coupling effect can be obtained in other ways, for example, by biasing tube 6 to cut-off at all times except when a signal is impressed on its grid, merely by the use of a reversing tube, or else by permitting tube 6 to draw current at all times and changing the magnitude thereof in accordance with the incoming signals. 45

For assigning the incoming signals to their respective channels, there is provided a rotating kicker disc 7 which may consist of any suitable 50

distributor arrangement for conductively closing an electrical circuit between the output of coupling tube 6 and the different channels in succession. It is preferred, however, to use a 5 commutator of the type described in United States Patent 1,963,587, granted June 19, 1934, to R. E. Mathes. In the particular arrangement shown, disc 7 comprises an insulating drum having attached to its periphery metallic wipers or brushes 10 which are arranged, as they revolve, to momentarily bridge, in succession, a plurality of pairs of contacts 13, 14, and thus close a circuit from tube 6, which is associated with all of the contacts 13, to the respective channels which are 15 individually connected through condensers 15 to the different contacts 14. Only two channels have been shown, but it will be understood that any desired number may be used. Kicker disc 7 is driven by a motor, not shown, which is maintained 20 in synchronism by the incoming signals. Although any well known method of synchronism may be utilized it is preferred to employ the system described in a copending application of R. E. Mathes, Serial No. 645,171, filed December 1, 25 1932.

In each receiving channel and in circuit with its respective condenser 15 is a locking circuit 8 for restoring the receiving signals to their original form as they appeared before transmission. 30 Since the locking circuit apparatus in each channel is the same, for the sake of simplicity, only a single channel circuit has been shown and will be described herein. The locking circuit comprises two electron discharge devices 16, 17 which are arranged to have two degrees of electrical 35 stability. These tubes are unstable when both are drawing current, but stable when one tube is passing current and the other blocking. The changing from one condition of stable equilibrium, such as when tube 16 is blocking and tube 40 17 is passing, to the other condition, when tube 16 is passing and tube 17 blocking, or the reverse, is caused by the presence of a suitable potential on the grid of tube 16 which is due, in this case, 45 to a charge on condenser 15, the latter, in turn, being in circuit with a resistance 11 connected to the anode of tube 6, and a resistance 19 in the grid circuit of tube 16 of the locking circuit. This locking circuit is more adequately described in 50 United States Patent 1,844,950 granted February 16, 1932 to J. L. Finch to which reference is made for a more detailed explanation of the operation thereof.

Coupled to the output terminals of the locking 55 circuit 8 may be any type of utilization circuit 18, such as a relay, an ink recorder, a printer, or local tone oscillator. This utilization circuit responds to the changes of polarity occurring in the output of 8 for marking and spacing conditions which, in turn, are due to the unbalance 60 of the locking circuit under its two degrees of stability.

The operation of the circuit is as follows:

Signals received over the antenna 1 are amplified and detected by apparatus 2 and arranged to 65 key an audible tone for transmission over land line 4 to the receiving station A at which the interrupted tone signals, corresponding to the incoming messages, are rectified and the envelope of the signals applied to the grid of tube 6. Filter 9 is used to smooth out any of the tone components remaining in the rectified signal. The application of the rectified signals on the grid of tube 6 drives the grid negative and causes the 70 tube to block, as a consequence of which no anode 75

current will flow through resistance 11, and the plate will be at its maximum positive potential. The kicker 7, which is driven in synchronism with the incoming signal, will now close the circuit from the anode of tube 6 through contacts 13 and 14, over brush or pin 12, to the condenser 15, thus charging the condenser. The application of this charge to condenser 15 causes a momentary flow of charging current into the condenser through a circuit including anode resistance 11 10 and grid resistor 19 of the locking circuit, thus enabling the application of a pulse of such polarity to the grid end of resistance 19 which will drive the grid of tube 16 positive. Tube 16 will now draw current, and due to the characteristics of 15 the locking circuit 8, tube 17 will be blocked. An electrical pulse of a predetermined polarity will thus be transmitted to utilization means 18 over lead 20. This pulse will continue until the conditions of tubes 16 and 17 of the locking circuit 20 reverse, at which time tube 16 will block and tube 17 pass current over lead 21 to the utilization circuit. Now, if at the next time the channel under consideration is assigned to the coupling circuit a signal is again being impressed on the grid of the 25 coupling tube 6, condenser 15 will remain charged and tube 16 of the locking circuit will continue to pass current. However, if at the time the channel is assigned to the circuit no signal is impressed on the grid of coupling tube 6, then 30 anode current will flow again through resistance 11 and will cause a drop of potential thereacross at the instant the contacts 13 and 14 are bridged by brush 12 of the kicker 7. Condenser 15 will now discharge over a path traced from $-E_c$, grid 35 resistor 19, through contacts 13, 14 and wiper pin 12, and into tube 6, thus causing the grid end of resistance 19 to become negative and allowing tube 17 to pass current while tube 16 blocks. In this manner, there is obtained a push-pull output 40 effect which operates the utilization means, and reproduces the original signal characters transmitted, which may be of the Morse code or any other suitable type.

It will be understood, of course, from a mere 45 inspection of the drawing that the invention is not limited to radio systems or to the precise arrangement of parts shown since land line systems may well be used and various modifications made in the circuits illustrated and described herein without departing from the spirit and scope of the appended claims.

I claim:

1. A receiving circuit for a multiplex telegraph system comprising a rectifying system for rectifying the received signals and having an output circuit, an electron discharge coupling device associated with said output circuit, circuit closing means for connecting at predetermined intervals the output of said coupling device to the various channels, said device being arranged to change its normal condition of electrical stability upon the flow of signal current in said rectifying system, storage means in each of said channels, the state of which is dependent upon the condition of said electron discharge device at the instant said device is connected through said circuit closing means to its associated channel, and utilization means individual to each channel under the control of said storage means.

2. A receiving circuit for a multiplex telegraph system comprising a rectifying system for rectifying the received signals and having an output circuit, an electron discharge coupling device 75

normally biased above cut-off to pass current associated with said output circuit, said device being arranged to become temporarily biased below cut-off upon the flow of signal current in 5 said rectifying system, storage means, circuit closing means for connecting the output of said electron discharge device at predetermined intervals to said storage means, and utilization means in circuit with said storage means.

10 3. A receiving circuit for a multiplex telegraph system comprising a rectifying system for rectifying the received signals and having an output circuit, an electron discharge coupling device normally biased above cut-off to pass current associated with said output circuit, said device being arranged to become temporarily biased below cut-off upon the flow of signal current in said rectifying system, a condenser, means for connecting the output circuit of said electron discharge device at predetermined intervals to said condenser, and utilization means in circuit with said condenser.

15 4. A receiving system for a multiplex telegraph system comprising a rectifying system for rectifying the received signals and having an output circuit, an electron discharge coupling device normally biased above cut-off to pass current associated with said output circuit, said device being arranged to become temporarily biased below cut-off upon the flow of signal current in said rectifying system, storage means, circuit closing means for connecting the output circuit of said electron discharge device at predetermined intervals to said storage means, a signal rebuilding system under control of said storage means comprising a plurality of electron discharge devices whose anodes and control electrodes are respectively interconnected, and a utilization circuit connected to said signal rebuilding system.

20 5. A receiving circuit for a multiplex telegraph

25 system comprising a rectifying system for rectifying the received signals and having an output circuit, an electron discharge coupling device normally biased above cut-off to pass current associated with said output circuit, said device being arranged to become temporarily biased below cut-off upon the flow of signal current in said rectifying system, a condenser individual to each channel of the telegraph system, circuit closing means for connecting the output circuit 10 of said electron discharge device at predetermined intervals to each of said condensers, signal rebuilding systems under control of said condensers comprising a plurality of electron discharge devices whose anodes and control electrodes are respectively inter-connected, and a utilization circuit coupled to each of said signal rebuilding systems.

30 6. A receiving system for a multiplex telegraph system comprising a rectifying system for rectifying the received signals and having an output circuit, an electron discharge coupling device normally biased above cut-off to pass current connected to said output circuit, a connection 20 from the anode of said electron discharge device to a source of positive potential, a resistance in said connection, a pair of contacts one of which is directly connected to said anode and the other of which is connected to a terminal of a condenser, circuit closing means for conductively connecting 25 at predetermined intervals said pair of contacts, a signal rebuilding system connected to the other terminal of said condenser comprising a plurality of electron discharge devices whose anodes 30 and control electrodes are respectively inter-connected, and a utilization circuit coupled to said signal rebuilding system.

35 ALFRED KAHN. 40
